THRESHING MACHINE FRAME

Hermann Raussendorf, Saxony, Germany

Application July 26, 1935, Serial No. 33,382
In Germany August 25, 1934

17 Claims. (Cl. 130—27)

This invention relates to frames for threshing machines in which the frame and supporting beams are constructed of steel.

In the ordinary threshing machines as now made a wood frame is provided resting upon longitudinal beams supported by the chassis. Such a construction, particularly when a straw press is connected with the threshing machine, is subject to twisting and torsion strains so that the connections between the various struts and beams are greatly strained and fail prematurely or become loosened by friction, etc. Attempts have heretofore been made to overcome these defects by providing the frame housing exteriorly with triangular metal plates in projecting or transverse beams as reinforcements, since it is impossible to provide transverse reinforcements at the interior of the housing with the exception of a few points. It is an object of the present invention to eliminate all the drawbacks inherent in constructions of the type mentioned.

Another defect in threshing machine frames as at present made lies in the fact that a wood frame is subject to a swelling and shrinking in accordance with humidity and other factors and this defect renders such a frame entirely unfit for use in tropical climates and also a wood frame in such climates would be soon destroyed by termites, etc. Attempts have been made in view of these conditions to construct a threshing machine frame of metal, particularly sheet metal, but such a construction has been no better than the ordinary wood frames. It is the purpose of the present invention to overcome all of the above named disadvantages of threshing machine constructions.

With respect to the threshing machine frames heretofore made of metal, it has been demonstrated in practice that such steel plate frames which are made of relatively weak plate and struts, beams or the like in order to reduce the weight, are not sufficient to withstand the great strains which are placed upon them. As the result of the strains to which this sheet metal construction is subjected, the rivet connections and nut and bolt connections, etc. are excessively overloaded and particularly the inner parts of the threshing machine which are connected with the wood frame are prone to become quickly incapacitated due to the twists and turns to which they are subjected. It is a further object of the present invention to eliminate all such drawbacks.

55 In contrast to the constructions heretofore used

the present invention proposes a completely new method of constructing a threshing machine frame in that two substantially U-shaped supporting yokes made of section beams, one located near the front and the other near the rear end of the threshing machine, are rigidly connected with a metallic under-frame which is strong enough to withstand the twisting and torsion actions set up. The arms of said U-shaped section beams are extended upwardly and carry the vertical lateral walls of the housing which in turn consist of steel plates passing entirely through and rigidly connected with the section beams.

It is an object of the invention to form a frame having three simple constructional parts, namely the underframe, the U-shaped supporting yokes and the side walls which, being supported by the usual and necessary transverse connections or beams, is completely rigid between the side walls and the construction is such that the underframe completely takes up all the strains which may be exerted upon the frame.

It is an object of the present invention to secure a construction which will permit the relative position of the frame to become changed when the threshing machine is traveling over rough ground or there has been an improper adjustment or alignment of the set up threshing machine. As the result of the construction those parts of the threshing machine located partly in the housing between the side walls and partly upon the side walls are not subject to any strain due to the turning or twisting of the threshing machine.

It is an object of the invention to form the underframe of a seamless drawn steel tube of suitable diameter while the U-shaped supporting yokes are made of section beams assembled from individual suitably bent flat steel strips.

It is a further object of the invention to provide means connected with the underframe by welding or the like forming a continuation extending along the longitudinal center of the threshing machine frame and in the form of a vertical section beam of sheet steel to which the transverse support on which the straw press frame is mounted may be attached.

A still further object of the invention is to mount the underframe by means of springs on the steel axles and to support it relative to the axle by a centrally mounted buffer spring.

A feature of the invention is to provide a construction whereby all parts of the frame may be

interconnected rigidly as for instance by electric welding.

With the above and other objects in view which will become apparent as the description 5 proceeds, a detailed explanation of an exemplary embodiment of the invention is described below and illustrated in the accompanying drawings.

Figure 1 is a lateral elevation of a threshing machine frame,

10 Figure 2 shows two relatively displaced vertical cross sections.

Figure 3 is a horizontal cross section upon the section line III—III of Figure 2 on an enlarged scale,

15 Figure 4 is a horizontal cross section on section line IV—IV of Figure 2 upon an enlarged scale,

Figure 5 shows the rear portion of Figure 1 upon an enlarged scale,

20 Figure 6 is a partial plan view of the parts shown in Figure 5,

Figure 7 is a cross section taken on the section line VII—VII of Figure 6,

25 Figure 8 is a cross sectional view of a detail taken on the section line XII—XII of Figure 5,

Figure 9 shows another portion of Figure 1 upon an enlarged scale illustrating the connection between the front axle and the metallic underframe upon enlarged scale,

30 Figure 10 is a side elevation of the view shown in Figure 9 on a somewhat reduced scale and looking in the direction of the arrow shown in Figure 9,

Figure 11 is a side elevation of a portion of 35 Figure 1 on an enlarged scale looking from the rear to the front and with the straw press together with its frame being omitted,

Figure 12 is a plan view of the construction shown in Figure 11 with portions omitted,

40 Figure 13 is a side view of a portion of the structure shown in Figure 12, and

Figure 14 is a vertical cross section taken on the section line XIV—XIV of Figure 11.

Referring to the drawings, the underframe 45 consists of a seamless drawn steel tube 1 which is located centrally between the wheels 2 and 3 and extends obliquely to the rear, being inclined at the end of the threshing machine at which the sheet steel frame of a straw press S may be connected with the threshing machine.

50 The front end of the tube 1 is mounted oscillatably upon the axle 4 upon which the wheels 2 are journalled. A buffer spring 5 is interposed. The rear end of the tube is supported upon the axle 6 upon which the wheels 3 are mounted and such rear end is resiliently mounted by means of the two sets of leaf springs 7.

Rigidly connected with the underframe or tube 1 are two substantially I-shaped or U-shaped 60 supporting yokes 8 and 9. The yoke 8 is located near the rear end in the vicinity of the axle 6 and the yoke 9 is provided near the front end in the vicinity of the axle 4. Referring to Figure 3 the supporting yoke 8 is of I-shape cross

65 section. Such cross section is formed by bending the three sheet metal strips, 10, 11 and 12 to the required yoke form and then welding them together electrically or securing them together by any other desired means. The plates 10 and 70 12 going from one side of the threshing machine to the other are closely applied to the periphery of the tubular underframe 1 and are connected therewith by electric welding or otherwise. The web of the I-frame is cut away in the manner shown particularly in Figure 2 so as to abut

closely the periphery of the tube 1 and the web 11 is then also secured by any desired means, preferably by electrical welding, to the tube 1.

As illustrated in the cross section of the yoke shown in Figure 4 the yoke 9 has a U-shaped cross section which is formed or assembled from three sheet metal strips 13, 14 and 15 which are electrically welded together. This cross section then changes into the same I-shaped beam as used in supporting yoke 8 at the lower portion 10 thereof and such construction is made by electrical welding three suitably bent sheet metal strips such as 16, 17 and 18. In this case also the connection with the underframe or tube 1 is the same as previously described with reference 15 to the supporting yoke 8.

The two vertical side walls 16 and 17 of the threshing machine frame are rigidly connected by electrical welding or any other desired means with the upwardly extending arms of the yokes 20 8 and 9. A transverse connection 18 between the two lateral walls having the welded, bent-down edges or flanges 16' and 17' is provided at the only place possible at the front end where the material to be threshed is fed. A transverse connection 19 is also provided in the vicinity of the concave.

As above described, it is obvious that all the parts of the threshing machine frame consist of sheet steel and are interconnected preferably by 30 electric welding. Any twisting or torsion turn which may arise can be completely taken up by the underframe 1 which is sufficiently strong to withstand the same. Moreover, any torsion strains or twisting strains are substantially lowered or weakened due to the spring 5 and the leaf springs 7. It is obvious that therefore due to the construction described the parts of the threshing machine located between the walls 16 and 17 of the frame are not effected by the 40 twisting or turning moments since the parallel spacings of the walls 17 and 18 is constantly maintained and ensured.

The walls 16 and 17 are provided with suitably shaped notches, depressions or cut-away portions for suspending the well known spring pins, 45 the springs 21 and 22 of which carry the shaker and the back travel floor. These springs are attached at their upper ends to the projections 23 of an angle bar 24 by bolts or screws and the like. The angle bar 24 is attached by the upper edge exteriorly on the side wall plate 16 and/or 50 17. The shaft 25 of the cylinder 26 cooperating with the concave 28 is mounted in a bearing located in a vertical longitudinal slot of the supporting yoke 9. It is for this reason that the upper ends of the yoke 9 are made U-shaped.

The wood platform 27 shown in dotted lines upon Figure 2 forms the upper closure of the threshing machine frame. This wood platform 60 may be retained since a metal platform does not provide a sure foothold for the workers and also because this frame is not subject to the strains previously mentioned.

Combined with the threshing machine frame 65 is the metallic straw press frame, the main portion of which forms the passage 29. The assemblage is constructed in the following manner, particular reference being made to Figures 5 to 8 inclusive.

A sheet metal member 30 is provided extending at its end 31 into the tubular underframe 1 to the inner wall of which it is electrically welded (see particularly Figure 7). The member 30 thus forms a projection or continuation extending 75

along the central longitudinal line of the threshing machine frame. The member 30 is reinforced at its lower edge by an arcuate flange 32 welded to the metal member 30 as shown in Figure 8. At the free end of the member 30 the angle members 33 are attached at both sides by means of welding. These angle members form supporting means for a transverse support 34 which is of U-shape and is secured as by bolts 10 and nuts or by screws to the angle members. Other supports also in the form of welded angle members 35 are provided at about the center of the member 30 at the upper edge thereof. A transversely extending beam 36 in the form of an angle bar or rail is screwed to these supports. The floor 37 of the straw press passage 29 is mounted upon the transverse supports 34 and 36.

A transverse beam or support 38 having a U-shaped cross section is welded to the under side of the steel tube 1 near the end at which the member 30 is secured. For increased reinforcement the sheet metal members or plates 39 are welded to the tube 1 and to a flange 40 of these members the transverse support 38 is attached by the screws 41. Secured to the ends of the transverse support 38 as by welding, are the vertical plates 42 having a flange construction 43. To each one of these plates 42 there is screwed or bolted a buttress-like or strut-like plate 44. The plates 30 44 extend upwardly and are welded to the corresponding lateral cheeks of the straw press passage 29. As will be noted, the metallic straw press frame is in this manner connected by a simple supporting rib structure with the frame 35 of the threshing machine so that any torsion is precluded. In this construction also all the parts as well as the section beams may if desired be made of steel plates which are welded together. On the underside of the sheet metal extension 30 45 there is welded an arm 45 having a perforation 46 whereby traction hooks, swingletree hooks or the like may be attached in case the threshing machine-straw press unit is to travel backwards. The spring suspension of the threshing machine frame is constructed in the following manner.

The front axle 4 consists of a box-like housing which is formed by a metal plate 48 with a channel-shaped member 47. On both sides of this housing the axle spindles 49 for the front wheels 2 are attached by welding. The front axle 4 constructed as a box-like housing above described is engaged at about its central portion by a U-shaped saddle or yoke 50 which is rotatably mounted with respect to the axle 4 by means 50 of the pivot pin 51. A tube or bearing 52 is welded in the center of the axle housing 4 and two plates 53 are welded upon the interior faces of the legs of the U-shaped yoke 50 in order to reinforce the bearing points.

Secured by welding to the U-shaped yoke 50 is the pivot pin 54 whose upper end enters a tube 55 which is welded in the steel tube or under-frame 1 which is somewhat flattened at the front end. Surrounding the pivot pin 54 is the conical buffer spring 5 resting upon the disk or plate 56. Interposed between the disk 56 and the U-shaped yoke 50 is the housing member 57 which is shouldered in the manner shown in Figure 9 and secured to the pivot pin 54 by means of the transverse pin 58.

A substantially U-shaped supporting yoke 59 is attached to the underframe 1 near the location of the pivot pin 54. The yoke 59 has a horizontal portion 59' which is reinforced by a plate 60 through which the housing member 57 extends.

The pivot pin 54 therefore serves as the pivot pin for the front axle. A reinforcement plate 61 is also provided being welded upon one hand to the underframe 1 and on the other to the yoke 59.

Bars 62 are welded to the front axle 4 and carry at their free ends a collar-like yoke 63 for inserting a thill, pole, beam or the like. Two V-shaped abutting bars 64 being welded on one hand to the axle 4 and on the other to the yoke 63 serve to reinforce the same.

The rear axle 6 also consists of a box-like housing in the ends of which the axle spindles 65 for the rear wheels 63 are secured as by welding. The supporting yoke 8 disposed above the rear axle 6 is supported by the two sets of leaf springs 15 7 which are secured to the yoke 8 by means of the shackle bolts 66. The ends of the leaf springs lie on the box-like housing of the rear axle 6 and are retained in place by the bolts or pins 67 which are inserted through apertures provided 20 in plates 68 which are in turn secured at both sides of the axle housing as shown particularly in Figure 14.

Upon the underframe 1 in the vicinity of axle 6 to spaced bars 69 are provided which receive 25 the axle housing between them. The bars 69 are preferably secured by welding to the underframe 1 and are in turn supported by the two reinforcing plates 70 welded between the bars and the yoke 8. Welded at both sides of the axle housing 6 are 30 two guide members 71 which are bent convexly relative to the guide bars 69. In this manner there is formed an upwardly and downwardly expanding guide passage for the bars 69 so that the bars 69 in addition to the vertical movement permitted can also have simultaneously a slight oscillation in a plane perpendicular to and parallel with the axle 6.

In addition, two struts 72 are attached by any 40 desired means such as the screws 73 to the rear axle 6. Welded to the tube 1 are two spaced bearing plates 74 and 75 between which the connecting member 76 is rotatably mounted by means of a pivot pin 77. The ends of the strut 72 are secured to the connecting member 76 by welding. The bearing plates 74 and 75 are supported by the supporting plates 78 shown particularly in Figure 13 which are welded on one hand to the bearing plates 74 and 75 and on the other hand 50 to the underframe 1.

In order that the threshing machine may rest firmly upon the chassis or frame during the threshing wood edges 79 are driven in between the wheels 3 and the arms of the supporting yoke 8. The wedges are shown in dotted lines in Figure 11. In order to accomplish this purpose bracket members 80 are welded to the yoke 8. In order when driving in wedges 79 not to exert unnecessary strain on the leaf spring 7, the tension screws 81 indicated by dotted lines in Figure 11 are first placed between the axle 6 and the yoke 8. For this purpose the yoke is provided with eyelets 82 and flaps 83 are provided upon the plates 68 therebelow, said plates 83 being provided with a perforation for an attaching screw.

I claim:

1. A threshing machine frame comprising a central torque member, substantially integral U-shaped supporting means fixedly secured to said 70 torque member and side walls secured to said U-shaped supporting means.

2. A threshing machine frame comprising a tubular metallic member, substantially integral U-shaped supporting means fixedly secured to 75

said torque member and side walls secured to said U-shaped supporting means.

3. A threshing machine frame comprising a tubular metallic torque member located substantially centrally of the frame, two substantially integral U-shaped supporting metallic yokes mounted upon said torque member, one of said yokes being located near the front of said torque member and the other located near the rear end 10 of said torque member and side walls secured to said supporting yokes.

4. A threshing machine frame comprising a seamless drawn tubular central torque member of sufficient strength to withstand turning 15 moments, substantially integral U-shaped supporting means fixedly secured to said torque member and side walls secured to said supporting means.

5. A threshing machine frame comprising a 20 seamless drawn tubular central torque member of sufficient strength to withstand turning moments, substantially integral U-shaped supporting means fixedly secured to said torque member and side walls secured to said supporting 25 means, said U-shaped supporting means being formed from flat metallic strips.

6. A threshing machine frame comprising a central torque member, substantially integral U-shaped supporting means fixedly secured to said 30 torque member, side walls secured to said U-shaped supporting means and resilient means supporting said torque member from the axles of the threshing machine.

7. A threshing machine frame comprising a central torque member, substantially integral U-shaped supporting means fixedly secured to said torque member, side walls secured to said U-shaped supporting means, a plate fixed to the 40 rear end of said torque member and transverse supports mounted upon said plate upon which the straw press frame may be mounted.

8. A threshing machine frame comprising a central torque member, substantially integral U-shaped supporting means fixedly secured to said 45 torque member, side walls secured to said U-shaped supporting means, a transverse support connected to said torque member at the vicinity of the rear end thereof and supporting plates fixed to said transverse support to which the side 50 walls of the straw press conduit may be attached.

9. A threshing machine frame comprising a central torque member, substantially integral U-shaped supporting means fixedly secured to said 55 torque member and a buffer spring substantially centrally located supporting the forward portion of said torque member from the front rotatable axle of the threshing machine.

10. A threshing machine frame comprising a central torque member, substantially integral U-shaped supporting means fixedly secured to said 60 torque member, side walls secured to said U-shaped supporting means and leaf springs located so as to support the rearward portion of said

torque member from the rear axle of the threshing machine.

11. A threshing machine frame comprising a central torque member, a guide sleeve positioned on said torque member and extending vertically 5 therefrom, a pivot pin disposed in said guide sleeve, means for rotatably mounting said pivot pin upon the front axle, a conical spring interposed about said pivot pin for supporting the forward portion of said torque member and substantially integral U-shaped supporting means fixedly secured to said torque member to which the side walls may be secured.

12. A threshing machine frame comprising a metallic central torque member, a pivot pin located at the said portion of said torque member, a conical spring cooperating with said pivot pin to resiliently support the said portion of said torque member, a U-shaped member fixed to the said portion of said torque member also cooperating with said pivot pin and substantially integral U-shaped supporting means fixedly secured to said torque member to which the side walls may be secured.

13. A threshing machine frame comprising a 25 central torque member, substantially integral U-shaped supporting means fixedly secured to said torque member, side walls secured to said U-shaped supporting means, a leaf spring fixed to said torque member at each side thereof at substantially the rearward portion thereof and shackle bolts securing the free ends of said springs to the rear axle.

14. A threshing machine frame comprising a central torque member, substantially integral U- 35 shaped supporting means fixedly secured to said torque member, side walls secured to said U-shaped supporting means, guide bars fixed to said torque member and guiding means for said guide bars located upon an axle of the threshing ma- 40 chine.

15. A threshing machine frame comprising a central torque member, substantially integral U-shaped supporting means fixedly secured to said torque member and walls for the housing of the 45 threshing machine fixed to said supporting means.

16. A threshing machine frame comprising a central torque member, substantially integral U-shaped supporting means fixedly secured to said 50 torque member, and means whereby wedges may be driven between the wheels of the threshing machine and said supporting means.

17. A non-twisting threshing machine frame comprising a tubular metallic underframe disposed substantially centrally of said frame, substantially U-shaped supporting means fixed to said underframe, a steel plate fixed to the rear end of said underframe disposed substantially vertical, an arcuate web plate fixed to the lower 60 edge of said steel plate, said plate and said web plate constituting an extension of said underframe.

HERMANN RAUSSENDORF.
